WASHING MACHINE AND DRIVE THEREFOR

Francis T. Johnson, Chicago, Ill., assignor to
 Chester T. M. Johnson and Martin F. W.
 Johnson, Chicago, Ill.

Application February 18, 1931, Serial No. 516,672

7 Claims. (Cl. 68—18)

My invention relates to an improvement in driving mechanisms adapted for driving washing machines. One object is the provision of a unitary structure in which motive means, such as 5 an electric motor, are associated with a driving mechanism, for example for a washing machine in which provision is made for drive in alternate directions. Another object is the provision of a simplified driving mechanism for changing the 10 direction of rotation alternately after a rotation through a predetermined period or number of revolutions. Other objects will appear from time to time in the course of the specification and claims.

15 I illustrate my invention more or less diagrammatically in the accompanying drawings, wherein—

Figure 1 is a side elevation;

Figure 2 is an end elevation;

20 Figure 3 is a top plan view of the mechanism, illustrating the washing machine in horizontal section; and

Figure 4 is a section on the line 4—4 of Figure 2.

Like parts are indicated by like symbols 25 throughout the specification and drawings.

Referring to the drawings, I illustrate a tub which includes a normally fixed cylinder A the ends of which are closed as by end portions A¹. This cylinder or tub is held against rotation and 30 may be mounted for example upon any suitable supporting end frame members generally indicated as A², which may ride for example on the rollers A³ on any suitable supporting surface A⁴. A⁵ indicates any suitable removable cover for 35 the top of the tub, whereby access may be had to the interior.

B indicates an interior movable or rotatable washing member, herein shown as including the foraminous cylinder wall B¹ mounted in rotatable 40 end plates B² the flange or peripheral bands of which are shown as at B³. Each such plate may be provided with a hub B⁴ from which projects outwardly a stub shaft B⁵ which may rotate for example in any suitable bearing B⁶ mounted on 45 or forming part of the frame A². Mounted on the shaft B⁵, as shown in Figure 3, and held against rotation in relation thereto is the spur gear B⁷.

As will be seen from Figures 1, 2 and 3, the 50 driving mechanism is mounted on a sub-frame structure which may include for example the angle member C bolted or otherwise secured to one of the A-frames A² and projecting at one end outwardly beyond it, as shown in Figure 2. 55 Resting on the angle member C and adjustable

therealong is an angle member C¹ which may be slotted as at C² to receive adjusting securing means such as the bolts C³. The adjustment may be affected as by the bolt C⁴ screwthreaded into the fixed member C⁵ mounted on the angle member C. This may be employed to tighten 60 the belt drive pulley below described. Upstanding from the adjustable angle member C¹ are the vertical angle members C⁶ C⁶. Spaced outwardly away from them are corresponding vertical angle members C⁷ C⁷, which may be arranged to 65 rest upon or be supported upon the supporting surface A⁴, as by the longitudinally extensible channel members C⁸ C⁸ which may be adjustably secured as by the bolts and nuts C⁹ passing 70 through slots C¹⁰. The uprights C⁶ and C⁷ are cross-connected horizontally as by the sleeves C¹¹ through which pass the bolts C¹².

Associated with the frame so formed is a motor D which may for example be mounted upon 75 transverse members D¹ D¹ mounted on angle members D² D³ which connect respectively the uprights C⁶ C⁶ and C⁷ C⁷. The motor may drive, as by the silent chain D⁴, passing about the motor sprocket D⁵, a sprocket D⁶ mounted on a shaft D⁷ which rotates in bearings D⁸ D⁸ mounted respectively on the frame members D⁹ D¹⁰. D¹¹ indicates a pulley the purpose for which will later be described. D¹² indicates any suitable manual switch whereby the motor may be controlled. 85

Mounted on the opposite arm of the A-frame A², as for example upon the outward projection or lug E is a bracket E¹ the upper end of which forms the lower half E² of the bearing sleeve the upper half of which E³ may be secured thereto. 90 An aligned bearing sleeve including the parts E⁴ E⁵ is mounted upon the bracket E⁶ secured to the lateral extension E⁷ from the A-frame. A brace made of the two parts E⁸ E⁹ extends from the member D⁹ to the bearing sleeve E³. The 95 part E⁹ has the adjusting screw E¹⁰ screwthreaded in the lug E¹¹ and engaging the upturned end E¹² of the part E⁸. The two parts of the brace are secured together by bolts E¹³ E¹³, the part E⁹ being slotted as at E¹⁴ to allow for adjustment of 100 the frame structure on which the motor is mounted.

Another brace is provided at the opposite side of the motor frame structure which consists of the threaded rod F screwthreaded in the lug F¹ mounted near the top of one of the uprights C⁶. One end of the rod F engages the lug F² on the bearing B⁶ and the opposite end is provided with a hand wheel F³. The hand wheel F³ may be ro- 110

tated to adjust the motor frame structure for tightening the belts.

Mounted in the bearing sleeves formed by the parts E² E³ E⁴ E⁵ is a shaft G. Secured against rotation in relation to it is a pinion G¹ in mesh with the spur gear B⁷ on the shaft B⁵ of the cylindrical washing member. Keyed on the shaft G is the intermediate pulley G². Rotatably mounted in relation to the shaft G, and positioned one on each side of the pulley G², are the loose pulleys G³ G⁴. Adjoining the pulley G⁴ is a worm G⁵ which may be formed on the hub of the pulley G⁴. Interposed between the end of the worm G⁵ and the bearing sleeve formed of the parts E² E³ is the member generally indicated as G⁷ which includes a hub portion G⁸ about the shaft G, in which the shaft may rotate, a downward extension G⁹ therefrom and an upward extension G¹⁰. Upwardly projecting from the platform G¹¹ are the lugs G¹² G¹³ in which is mounted a rod G¹⁴. Slidable along the rod is a shift structure G²¹ including the members G¹⁵ G¹⁶ through which the rod passes. Extending outwardly therefrom are the belt control arms G¹⁷ G¹⁸. G¹⁷ terminates in an eye G¹⁹ and G¹⁸ terminates in a belt engaging finger or loop structure G²⁰. The shift structure G²¹ has a rearwardly projecting finger G²³ underlying a guide block G²⁴ on the table or platform G¹¹ which prevents the shift structure tilting as it slides on the rod G¹⁴. The shift member may be moved along the rod G¹⁴ as by the control arm H which is pivoted as at H¹ upon the downward extension G⁹ from the hub G⁸ and is guided near its upper end in the slot G²² in the forward edge of the table G¹¹. At its upper end it is provided with an enlargement H² notched as at H³ to receive the latch H⁴ pivoted as at H⁵ upon or adjacent the member G¹⁶. The latch may be moved into or out of operative engagement as by the manual handle H⁶. Intermediate the member H is a cam aperture generally indicated as H⁷. Rotatably mounted on the upward extension G¹¹ is a worm gear H⁸ in mesh with the worm G⁵. It is provided with an outwardly extending cam member H⁹ adapted to engage the interior of the cam aperture or loop H⁷. Rotation of the worm gear H⁸ in response to rotation of the worm G⁵ causes the arm H to oscillate about its pivot H¹, thereby moving the belt control mechanism in one direction or the other along the rod G¹⁴, if the above described latch mechanism including the latch H⁴ is engaged. For example, in Figure 4, with the gear H⁸ rotating in clockwise direction, the cam member H⁹ has moved the arm H to the limit of its movement toward the right, bringing the belt J onto the pulley G².

J indicates a belt shown as in Figures 3 and 4 as extending about the pulley G² and also as passing through the loop G¹⁹ of the belt controlling arm G¹⁷, and about the pulley D¹¹. J¹ indicates another belt, shown in Figures 3 and 4 as passing about the pulley G⁴, through the loop G²⁰, and about the pulley D¹¹. The belt J¹ is shown as twisted being therefore adapted to serve as a direction reversing device in relation to the belt J.

In the normal operation of the device, assume that the motor D is constantly driving the shaft D⁷ and through it the pulley D¹¹. The belts J, J¹ will therefore constantly be driven but, so far as relates to their effect on the pulleys G² G³ or G⁴, in opposite directions, owing to the twisting of the belt J¹. In the position in which the device is shown in Figure 4 the belt J is driving the foraminous cylinder B¹ of the washing machine, since it engages the pulley G² which is keyed to the shaft G, the shaft G being in a constant driving relation with the washing machine. The belt J¹ is driving the pulley G⁴ but this drive is without direct effect on the rotation of the foraminous cylinder B¹ since the pulley G⁴ is loose on the shaft G. The worm G⁵, however, is constantly rotated by the pulley G⁴ and serves to maintain a constant driving connection with the worm gear H⁸. As above explained, constant rotation of the worm gear will oscillate the control arm H about its pivot H¹. As the belt control structure moves left, referring to the parts in the position in which they are shown in Figures 3 and 4 the belt J will be moved on to the idler pulley G³ and the reverse twisted belt J¹ will be moved into driving connection with the drive pulley G². The result will be a reversal in the direction of drive of the foraminous cylinder B¹ which will be maintained until rotation of the worm gear H⁸ moves the cam H⁹ into position to oscillate the arm H back into the position in which it is shown in Figure 4. By proportioning the size, shape and relationship of the cam loop H⁷ and the cam member H⁹ and by proportioning the size and pitch of the worm and the gear teeth a wide range of control is possible. Preferably the parts will be so formed that the foraminous cylinder B¹ will be rotated through any desired number of rotations in one direction. This rotation will be followed by a reversal, after the shift of the mechanism and the change of direction of drive and the foraminous cylinder will then be rotated for a similar number of revolutions, in the opposite direction. This drive is independent of direct control or attention by the operator. The belt J¹ is of sufficient width to overlap onto the pulley G⁴ when it is shifted to the left onto the pulley G² thereby giving a constant drive to the pulley G⁴ and worm G⁵.

In order to provide any desired tension upon the belts or to compensate for stretching of the belts or replacement by belts of different size, I have illustrated an adjusting means for the motor and pulley D¹¹ as adjustable toward and away from the drive shaft G, as by movement of the channel C¹ in relation to the channel C and also by adjustment of the connection between the brace E⁸ and the member D⁹.

Note also that if desired this alternate drive connection may be interrupted. For example the latch H⁴ may be swung into position in which it is shown in dotted line in Figure 2 between the upstanding lugs H¹⁵. The result will be to render the oscillation of the shaft H inoperative, so far as concerns the belt shift as the belts are then in a neutral position on the loose pulleys G³ and G⁴. For example the drive mechanism may be locked in inoperative position and the tub may be locked against further rotation by means of the latch member H¹⁶ pivoted as at H¹⁷, which may be rotated or dropped into position in engagement with teeth of the spur gear B⁷. The tub may thus be held positively against rotation to permit removal of the cover A⁵ and change of the wash and the like.

It will be realized that whereas I have described and shown a practical and operative device, nevertheless many changes may be made in the size, shape, number and disposition of parts without departing from the spirit of my invention. I therefore wish my description and drawings to be taken as in a broad sense illustrative and diagrammatic rather than as limiting me to my specific showing.

I claim:

1. In a drive mechanism for a washing machine which includes a rotatable part, a drive shaft mounted upon said washing machine structure, a driven shaft mounted upon said washing machine structure, a drive pulley and a driven pulley, motor means for rotating said drive shaft and drive pulley, a driving connection between said driven pulley and the rotatable part of the washing machine, a plurality of belts in normally constant driving relation with the drive pulley, both of said belts being adapted for drive engagement with said driven pulley, one of said belts being twisted to impart a reverse movement to said driven pulley when it is in driving relation therewith and means for shifting said belts, in normally continuous cycle, for alternate engagement with said driven pulley, and means for adjusting the driving and driven pulleys toward and away from each other. 80
- 5 10 15 20 25 30 35 40 45 50 55 60 65 70 75 80 85 90 95 100 105 110 115 120 125 130 135 140
2. In a drive mechanism for a washing machine which includes a rotatable part, a drive shaft mounted upon said washing machine structure, a driven shaft mounted upon said washing machine structure, a drive pulley and a driven pulley, motor means for rotating said drive shaft and drive pulley, a driving connection between said driven pulley and the rotatable part of the washing machine, a plurality of belts in normally constant driving relation with the drive pulley, both of said belts being adapted for drive engagement with said driven pulley, one of said belts being twisted to impart a reverse movement to said driven pulley when it is in driving relation therewith and means for shifting said belts, in normally continuous cycle, for alternate engagement with said driven pulley, and a sub-frame, mounted upon the washing machine, said motor means comprising a motor mounted on said sub-frame, a drive shaft rotatably mounted upon said sub-frame, the drive pulley being associated with said drive shaft and a normally constant driving connection between said motor and drive shaft, said sub-frame being bodily adjustable in relation to said washing machine. 105
3. In combination with a washing machine, having a frame, whereby it is mounted, a sub-frame, power means including a driving pulley mounted upon said sub-frame, a second sub-frame mounted upon said washing machine, a driven shaft carried in said second sub-frame, driving means connecting said driven shaft with said first mentioned driving pulley, adjustable spacing members between said first and second sub-frames, whereby the two may be adjusted toward and from each other, the adjustment of said sub-frames being independent of the application of power to said driving pulley from said power means. 120
4. In combination with a washing machine, having a frame, whereby it is mounted, a sub-frame, power means including a driving pulley mounted upon said sub-frame, a second sub-frame mounted upon said washing machine, a driven shaft carried in said second sub-frame, driving means connecting said driven shaft with 125

said first mentioned driving pulley, adjustable spacing members between said first and second sub-frames, whereby the two may be adjusted toward and from each other, the adjustment of said sub-frames being independent of the application of power to said driving pulley from said power means, and adjustable supporting members on said first sub-frame, whereby said frame may be in part supported directly from the surface which supports the washing machine. 85

5. In combination with a washing machine, having a frame whereby it is mounted, a sub-frame positioned upon said washing machine frame, power means and a driving pulley mounted upon said sub-frame, a second sub-frame mounted upon said washing machine, a driven shaft carried in said second sub-frame and operatively connected to a moving part of the washing machine, driving means connecting said driven shaft with said first mentioned driving pulley, adjustable spacing members between said first and second sub-frames, whereby the two may be adjusted toward and from each other, the adjustment of said sub-frames being independent of the application of power to said driving pulley from said power means, and adjustable supporting members on said first sub-frame, said adjustable supporting members extending to the surface which supports the washing machine and being adapted, in part, to support said frame there- 100

upon. 95

6. In combination with a washing machine, having a frame whereby it is mounted, a sub-frame adjustably positioned upon said washing machine frame, power means and a driving pulley mounted upon said sub-frame, a driving belt between the power means and the driving pulley, a second sub-frame mounted upon said washing machine, a driven shaft and pulleys carried in said second sub-frame, belts connecting said pulleys with said first mentioned driving pulley, and adjustable spacing members between said first and second sub-frames, said spacing members being adapted to space said sub-frames in a plurality of adjusted positions. 105

7. In combination with a washing machine, having a frame whereby it is mounted, a sub-frame adjustably positioned upon said washing machine frame, power means and a driving pulley mounted upon said sub-frame, a driving belt between the power means and the driving pulley, a second sub-frame mounted upon said washing machine, a driven shaft and pulleys carried in said first sub-frames, belts connecting said pulleys with said first mentioned driving pulley, adjustable spacing members between said first and second sub-frames, whereby the two may be adjusted toward and from each other without affecting the tension of the first mentioned belt, and adjustable supporting members on said first sub- 130

frame, said adjustable supporting members extending to the surface which supports the washing machine and being adapted, in part, to support said frame thereupon. 135

FRANCIS T. JOHNSON. 140
